INVENTOR:
WILHELM HENNING PETERSÉN

BY
Wallace White
ATTORNEY.

UNITED STATES PATENT OFFICE.

WILHELM HENNING PETERSÉN, OF LUDVIKA, SWEDEN, ASSIGNOR TO ALLMÄNNAN
SVENSKA ELEKTRISKA AKTIEBOLAGET, OF VÄSTERAS, SWEDEN, A CORPORATION
OF SWEDEN.

INVERSE TIME-LIMIT RELAY.

Application filed December 1, 1926, Serial No. 151,952, and in Denmark July 3, 1926.

In my patent application Serial No. 472,-
848 I have described an induction type
time limit relay which has an operating
device pivoted in a member capable of being
5 rocked into a position for engagement with
the releasing mechanism by immediate
action of the driving forces acting on the
operative member.

As the said forces, according to the law of
10 action and reaction, act not only on the
member which in the specification forming
part of patent application 472,848 has been
designated as the induction member, but
also on the electromagnet and on the brak-
15 ing magnet, an analogous action is obtained,
if the rotatable induction member is caused
to turn on fixed pivots, and on the other
hand, one of the said magnets is caused to
swing and thereby to bring the gearing into
20 engagement. Such a modification of the
original arrangement forms the object of the
present invention.

A form of the invention, in which the
25 braking magnet is rotatable, is illustrated in
the accompanying drawing in two views
perpendicular to each other in Figs. 1 and 2.

1 is the electromagnet provided with a
short-circuited auxiliary coil ("shading
30 coil") 2, under the influence of which the
induction disc 3 is kept in rotation in the
direction of the arrow (Fig. 1). The speed
is limited by a braking magnet 4, which thus
normally exerts a torque on the disc equal to
35 that exerted by the electromagnet (not
counting the unimportant friction forces)
and within normal limits substantially pro-
portional to the speed and to the operating
current. When the latter exceeds a certain
40 value, the force acting between the disc and
braking magnet will be so great as to over-
come the tension of a spring 5 acting on the
latter and to rotate the magnet which rests
on a pair of pivots 6, until it is checked by a
45 stop 7. The magnet carries a bearing 8 for
a helical gear segment 9, which is caused
to partake in the swinging movement and
then comes into engagement with a screw
10 on the shaft 12 of the disc 3, said shaft
rotating in fixed bearings 11. The segment

then begins to rotate around its axis and 50
after a certain time strikes a movable con-
tact 13 and presses it against a fixed one 14
in analogy with the action described in ap-
plication No. 472,848. 15 is an adjustable
stop for regulating the starting point of 55
the motion of the segment and thereby the
time for release.

I claim as my invention:

1. In inverse time limit relays, an electro-
magnet, a braking magnet, an operating 60
device kept in rotation about a stationary
axis under the influence of induction forces
from said electromagnet and braking forces
from said braking magnet, one of said mag-
nets being capable of a swinging movement 65
under the reaction force from said operating
device.

2. In inverse time limit relays, an electro-
magnet, a movable braking magnet, an oper-
ating device kept in rotation about a 70
stationary axis under the influence of induc-
tion forces from said electromagnet and
braking forces from said braking magnet,
the latter being capable of a swinging move-
ment under the reaction force from said 75
operating device.

3. In inverse time limit relays, an electro-
magnet, a braking magnet, an operating
device kept in rotation about a stationary 80
axis under the influence of induction forces
from said electromagnet and braking forces
from said braking magnet, and a releasing
mechanism carried by one of said magnets
and capable of being engaged by said oper-
ating device by rocking said magnet. 85

4. In inverse time limit relays, an electro-
magnet, an operating device kept in rotation
about a stationary axis by induction from
said electromagnet, a braking magnet 90
capable of being swung around an axis, and
a releasing mechanism carried by said brak-
ing magnet and capable of being engaged
by said operative device by rocking said
magnet.

In testimony whereof I have signed my 95
name to this specification.

WILHELM HENNING PETERSÉN.
